[57] ABSTRACT

A traveling grate for heat treating materials having an endless chain grate with lateral side plates to convey the materials on its upper strand through a heat treating chamber and wherein the chain grate is provided with upstanding side plate members at its lateral edges, each of the side plate members having therein vertical slots open at their upper ends to permit thermal expansion and contraction of such members.

TRAVELING GRATE FOR HEAT TREATING MATERIALS

Traveling grates of the endless chain type are employed in heat treating procedures of widely different kinds of goods, for example, crude ore, cement raw meal, or fertilizer, whereby these materials might be processed in granular form or as pellets. The material to be treated is conveyed on the upper strand of an endless chain grate through the heat treating chamber, which may have a gas temperature range between 800° – 1,200° C. Whereas the individual members of the chain grate are protected from these high temperatures by the layer of the material to be treated, the lateral side plate members, being higher than the chain members of the chain grate, have considerably less protection or none at all from these temperatures, since the layer of the material slopes at the lateral edges as a result of friction at the wall, and thus cannot protect the upper edges of these side plate members at all or at least only very incompletely. On the other hand, the space beneath the upper strand of the chain grate is exposed to temperatures between 200° – 600° C, so that at least the upper side of the side plate members facing the heat treating chamber are subjected to a considerably stronger heating than is the lower side of the side plate members facing away from the heat treating chamber. It follows, therefore, that high thermal stresses occur within the side plate members, which stresses could easily lead to a destruction of the side plate members, which in turn would cause undesirable interruption of the operation.

An object of the present invention is to construct a traveling grate of the type referred to and wherein destruction of the side plate members of chain grates caused by thermal stress is largely prevented.

In accordance with the invention, the side plate members are provided with slots to accommodate expansion and contraction at the side facing the heat treating chamber. By locating these expansion slots in the upper portion of the side plate members, it is possible to reduce thermal stress considerably so that resulting destruction of the side plate members and subsequent interruption of the operation of the traveling grate can be largely eliminated.

An embodiment of the invention is shown in detail in the following description and drawings wherein:

FIG. 1 is a simplified partial cross section of a traveling grate according to the invention; and

FIG. 2 is a side elevation view of a side plate member according to the invention.

For purposes of simplification, FIG. 1 illustrates merely that portion of the traveling grate equipment 1 of the invention, through which upper strand 2 of a continuously revolving chain grate 3 is conveyed perpendicularly to the plane of the drawing. A layer of material 4 is located on the top side of the upper strand 2, which material is conveyed through the heat treating chamber 5 located above the upper strand 2 of the chain grate where gas temperatures of approximately 800° – 1,200° C prevail, while gas temperatures of approximately 200° – 600° C prevail in the region below the upper strand 2 of the chain grate. The chain members 6 (with grates) sequentially adjacent to each other in the direction of motion of chain grate 3, are linked to each other by means of grate bolts 7 (merely indicated by a center line), whereby, depending upon the

width of the traveling grate, a corresponding number of chain members 6 are arranged side by side on the grate bolt 7.

The lateral edges of the grate chain 3 have side plate members 8, 8', which are linked to each other with their ends overlapping by means of grate bolts 7 in the same manner as are the chain members 6. As can be readily seen from the drawing, side plate members 8, 8' extend to a higher level than that of the chain grate members 6 whereby a lateral boundary is formed for the layer of material 4 which slopes slightly in this boundary region. Lateral walls 1a and 1b of traveling grate equipment 1 furthermore contain channels 9, 9' for guiding the chain grate 3 with its lateral edges, including side plate members 8, 8'.

FIG. 2 illustrates a single side plate member 8 in side elevation; side plate members 8' on the other lateral edge of chain grate 3 are constructed likewise, but in mirror symmetry. Side plate member 8 contains in its lower half boreholes 10, 10' for providing a flexible connection of successive neighboring side plate members 8, as well as for accepting the grate bolts.

For purposes of providing the side plate members, despite great differences in temperature between their top and bottom sides (with respect to the top and the bottom sides of the upper strand 2 of the chain grate), with a comparatively large resistance to great thermal stresses, i.e., to enable them to accept large thermal stresses without breaking, the side plate members are provided at their upper edge 11, at the side facing heat treating chamber 5, with slots 12 to accommodate expansion and contraction. The number of such expansion slots 12 will generally depend upon the size of the chain grate and thus upon the size of the side plate members; the embodiment illustrated provides for two slots 12. The expansion slots 12 provided in the upper half of side plate member 8 are located between two vertical planes 10a and 10'a, which traverse the center axes of the pivoting point, in this instance the center axes of the boreholes 10, 10'. It is advantageous for the expansion slots 12 to be located a distance A away from vertical planes 10a and 10'a, said distance A corresponding at least to the radius of boreholes 10, 10' of side plate member 8. Each expansion slot 12 is open at the top side 11 of side plate member 8, and in this instance runs about perpendicular to the side plate member, said slot having a length L of approximately 0.3 to 0.5 times the value of the total height H of the side plate member 8.

The side plate member 8 illustrating the invention is only slightly weakened by the construction and arrangement just described of the slots 12 to accommodate expansion and contraction. For side plate members that are more heavily stressed, it is possible to compensate any resulting weakening without difficulty, by providing suitable reinforcing ribs.

In conclusion it should also be mentioned that individual side plate members are advantageously shaped at the longitudinal axis such that sequentially adjacent side plate members interlock, thus forming on both sides an almost smooth surface covering slots 12 to prevent the escape of gases. Such forming furthermore makes the individual side plate members more rigid.

What is claimed is:

1. Traveling grate for heat treating materials conveyed through a treatment chamber comprising a continuous chain grate; and elongate upstanding side plate

members at the lateral edges of said chain grate, each of said side plate members having slots therein open at their upper ends to accommodate expansion and contraction.

2. Traveling grate according to claim 1 wherein each of said side plate members has a pair of holes for the reception of bolts, and wherein said slots are located in the upper half of each side plate member and between the two vertical planes traversing the center axes of said holes.

3. Traveling grate according to claim 2, wherein said expansion slots are located at a distance away from said vertical planes corresponding at least to the radius of said holes of the side plate member.

4. Traveling grate according to claim 1 wherein each of said side plate member extends to a level higher than that of the chain grate, and wherein said slots have a length approximately 0.3 to 0.5 times the value of the total height of the side plate member.

5. Traveling grate according to claim 4 wherein said slots extend perpendicularly from the upper edge of said side plate member.

6. Traveling grate for heat treating materials conveyed through a treatment chamber comprising a continuous chain grate; and upstanding, elongate side plate members at the lateral edges of said chain grate and having their adjacent ends in overlapping relation, each of said plate members being alike and having a body provided adjacent its opposite ends with a pair of spaced apart holes therein for the reception of bolts, each of said plate members having therein a pair of spaced apart slots extending from the upper edge of said plate member toward but terminating short of the lower edge thereof, said slots being located between said holes, the locations of said holes and the locations of said slots being such that the overlapping ends of adjacent plate members cover said slots.
